US00D527043S

(12) **United States Design Patent** (10) **Patent No.:** **US D527,043 S**
Borne et al. (45) **Date of Patent:** **** Aug. 22, 2006**

(54) **LABEL PRINTER**

(75) Inventors: **Bradley W. Borne**, Uniontown, OH (US); **Robert L. Leonard, Jr.**, Canal Fulton, OH (US); **Tracey L. Glenn**, Altadena, CA (US)

(73) Assignee: **Avery Dennison Corporation**, Pasadena, CA (US)

(**) Term: **14 Years**

(21) Appl. No.: **29/210,224**

(22) Filed: **Jul. 27, 2004**

(51) **LOC (8) CI. 18-02**

(52) **U.S. Cl. D18/50; D18/19**

(58) **Field of Classification Search** D18/19, D18/36-39, 50, 54, 54.1, 55; D14/420-425, D14/462-470; 40/613, 613.1, 613.2, 613.3, 40/613.4, 690.1, 690.2, 690.3, 690.4, 691-694

See application file for complete search history.
